(57) **CLAIM**

The ornamental design for a charging case, as shown and described.

DESCRIPTION

FIG. 1 is a top, front, left side perspective view of a charging case showing our new design;

FIG. 2 is a bottom, rear, right side perspective view thereof;

FIG. 3 is a front elevation view thereof;

FIG. 4 is a rear elevation view thereof;

FIG. 5 is an enlarged left side elevation view thereof;

FIG. 6 is an enlarged right side elevation view thereof;

FIG. 7 is a top plan view thereof;

FIG. 8 is a bottom plan view thereof;

FIG. 9 is a perspective view of the charging case shown in an open position and in a state of use;

FIG. 10 is an enlarged view of an encircled portion of the charging case labeled **10** in FIG. 1; and,

FIG. 11 is an enlarged view of an encircled portion of the charging case labeled **11** in FIG. 2.

The evenly-dashed broken line showing of an electronic cigarette in FIG. 9 depicts environmental structure and forms no part of the claimed design. All other evenly-dashed broken lines shown in the drawings depict portions of the charging case that forms no part of the claimed design. The dot-dash broken lines represent boundaries of the enlarged portions and form no part of the claimed design.
